CLAMP FOR ELECTRICAL CONDUIT

Thomas Mooney, Mount Sinai, and Stephen Veselaski, Shirley, N.Y., and John Clark, Willow Springs, Ill., assignors to I-T-E Imperial Corporation, East Farmingdale, N.Y.

Filed Apr. 17, 1975, Ser. No. 569,298

Term of patent 14 years

Int. Cl. D8—08

U.S. Cl. D8—235

Fig. 1.

Fig. 2.

Fig. 3.

FIG. 1 is a left side perspective view of a clamp for electrical conduit, the broken lines of a conduit being for illustrative purposes only.

FIG. 2 is a right side elevational view thereof; and FIG. 3 is a rear elevational view thereof.

We claim:

The ornamental design for a clamp for electrical conduit, as shown and described.
